BACK WASHER

Bert E. Large, Lincoln, Nebr.

Application December 5, 1938, Serial No. 244,011

6 Claims. (Cl. 4—184)

The present invention is concerned with a back washer and more particularly with a back brush attachment for a bath tub.

The difficulties encountered by a bather in washing his back are well known. While special long handled brushes are provided for this purpose, these brushes are, nevertheless, extremely inconvenient to use. Because of this, various forms of attachments for bath tubs have been provided for this purpose. These attachments have been undesirable either because of the amount of space in the bath tub taken by the attachment, the awkward manner in which these attachments must be manipulated, or the complication thereof. For the above reasons, these attachments have not gone into general use.

An object of the present invention is to provide a back washer attachment of improved design that, except for the washer itself, extends closely adjacent the edge of the tub and is convenient to use.

A further object of the invention is to provide a back washer which is relatively balanced in construction so that the only weight which must be actuated is that of the brush itself, as in the case of the ordinary hand brush.

A further object of the invention is to provide a back washer which is extremely simple in construction and which is readily clamped on any type of tub.

Other objects of the invention will be apparent from the accompanying specification, claims, and drawing of which:

Figure 1 is a longitudinal sectional view of a bath tub to which is secured the improved back washing attachment and in which is seated a bather using the attachment.

Figure 2 is an elevational view of the back washer attachment with a portion of the side of a bath tub shown in transverse section, and in which

Figures 3 and 4 are detail views of alternative forms of the clamp forming a part of the attachment.

Referring to the drawing, the reference numeral 10 is employed to designate a bath tub shown in longitudinal section in Figure 1. The tub is of the conventional type having a rolled rim 11 and suitable supporting members 12 and 13.

The attachment forming the present invention is best shown in Figure 2. Referring to that figure, it will be noted that the attachment comprises a clamp 15 to which a rod 16 is secured intermediate the ends thereof. The rod has a

knob 17 rotatably secured to one end thereof and is bent at its other end to provide a transversely extending portion 18 on which is secured a brush 19 or other suitable back washing device.

The form of the clamp shown in Figure 2 is illustrated in somewhat greater detail in Figure 3. As best shown in that figure, the clamp comprises a curved upper portion 21, a flat side portion 22, an inturned lower flange portion 23, and a second side portion 25. The side portion 16 is offset from the curved portion 21 by a horizontal shoulder portion 26. Projecting outwardly from the side portion 22 is a cylindrical boss 27. An aperture 28 extends through the boss 27 and the side portion 25. The boss 27 serves as a bearing for the rod 16 which is pivoted to the clamp at this point by a rivet 30 or other suitable fastening means extending through the aperture 28. The offsetting of the side portion 25 provides space between the clamp and the tub 10 for the inner head of the rivet 30 and decreases the possibility of injury to the tub arising from careless application of the clamp thereto.

Secured on the inner surface of the curved portion of the clamp are a pair of felt strips 32. These felt strips engage the upper curved surface of the rolled edge 11 as indicated in Figure 2. A thumb screw 34, provided with the usual thumb piece 35 extends through the flange 23 and carries a bearing plate 37 at its upper end. 30 A block of wood 38 bears against the under surface of the rolled edge 11, the block being curved in conformity with the curvature of edge 11.

The knob 17 is a relatively flat spheroid and is pivotally secured to the rod 16 by a rivet 40, or other suitable fastening means. A spacer 41 is interposed between the knob 17 and the rod 16 to facilitate free rotation of knob 17. It will be noted that the knob 17, by reason of its relatively flat form projects only slightly from the rod 16. 40 It will further be noted that rod 16 extends closely adjacent the side of the tub 10, and this is true regardless of the angular position of rod 16.

The brush 19 may be detachably secured in any conventional manner to the transversely extending portion of rod 16 to permit the substitution of other brushes or other washing appliances.

It will be noted that the distance of knob 17 from the axis of rotation of rod 16 is substantially the same as the distance of the brush surface from such axis of rotation. This feature has a dual function. In the first place, the linear motion of the brush corresponds in magnitude 55

to the linear motion of the knob producing it, and thus results in a more natural action. It will be obvious that, if the motion of the brush is much greater than the motion of the knob or vice versa, it will be extremely difficult for the bather to become accustomed to the operation of the device. In the second place, this feature results in the device being substantially balanced except for the greater weight of the brush with respect to the knob. Thus in effect, the only weight the bather is moving is that of the brush itself. This results in little physical effort being necessary to operate the device, and also results in the operation being more analogous to that in which a brush is used directly. This again, increases the ease with which the bather may become accustomed to the use of the device.

In Figure 1, the device is shown in actual use by a bather designated by the numeral 45. It can be readily seen from this figure that the back brushing operation is extremely simple and natural. It will furthermore be seen that the arcuate path of the brush roughly corresponds to the curvature of the back so as to require a minimum amount of shifting of the body.

The clamp shown in Figures 2 and 3 is the one most adapted for use on a bath tub having a rolled rim. The clamp shown in Figure 4 is used in connection with a square edge bath tub. This clamp comprises two inverted L-shaped clamping members 47 and 48. The horizontal legs of the clamping members are superimposed. The horizontal leg of clamping member 48 is provided with a slot 49. A thumb screw 50 extends through this slot and into a threaded aperture of the horizontal leg of clamping member 47. The inner face of the vertical leg of clamping leg 48 is provided with a felt facing 51. A leaf 52 of resilient metal is secured at its center to the inner face of the vertical leg of clamping member 47, and secured to this leaf is a felt facing 53. The vertical leg of clamping member 47 is provided with two ears 54 through which extend thumb screws 55. This vertical leg of clamping member 47 is also provided with a boss 57 corresponding to the boss 27 of the other form of the clamp. It is to be understood that the rod 16 is connected to boss 57 in the same manner as it is connected to the boss 27 of the form of Figure 2.

In the application of the clamp of Figure 4 to a bath tub, the thumb screw 50 is loosened and the two clamping members 47 and 48 are slid together so as to loosely engage the opposite sides of the side wall of the bath tub. The thumb screw 50 is then tightened, and the two thumb screws 55 are screwed inwardly to complete the clamping action. The screwing in of these thumb screws forces the resilient leaf 52 inwardly, pressing the felt 53 against the side of the tub. It will be noted that both clamping surfaces have a felt facing so that there is no danger of injury to the finish of the tub.

It will be seen that I have provided a new and novel back washer attachment which is extremely simple in construction. The construction is such, moreover, that it is extremely easy to become accustomed to the use of the attachment.

While I have shown certain specific embodiments of my invention, it is to be understood that this is only for purposes of illustration, and that the invention is limited only by the scope of the appended claims.

I claim as my invention:

75 1. A bath brush attachment comprising a

clamp adapted to engage the side of a bath tub, a rod pivoted to said clamp at a point such that when said clamp is secured to a tub said rod extends substantially its full length closely adjacent the side of the tub to which said clamp is secured, said rod being pivotably movable about an axis substantially transverse to said rod in a substantially vertical plane extending longitudinally of the tub, said rod being provided with a handle portion and a portion disposed transversely with respect to the remainder thereof, and a brush secured to said transversely extending portion of the rod.

2. A back washer attachment comprising a clamp adapted to engage the side of a bath tub, 15 a rod pivotally secured intermediate its ends to said clamp and pivotally movable in a vertical plane about an axis substantially transverse to said rod, a handle secured to said rod at one end, said rod being provided at its other end 20 with a portion extending transversely to the remainder thereof, and a back washer carried by said transversely extending portion, said handle and said washer being located at approximately the same distance from said pivot point so that 25 the apparatus is substantially balanced disregarding the relative weights of the handle and washer.

3. A back washer attachment comprising a clamp adapted to engage the side of a bath tub, 30 a rod pivoted intermediate its ends to said clamp at a point such that when said clamp is secured to a tub said rod extends substantially its full length closely adjacent the side of the tub to which said clamp is secured, said rod being pivotally movable about an axis substantially transverse to said rod in a substantially vertical plane 35 extending longitudinally of the tub, a knob secured to said rod at one end thereof and serving as a handle for movement of said rod, the other end of said rod being disposed transversely with respect to the remainder thereof, and a back washing device secured to said transversely extending portion of the rod.

4. A back washer attachment comprising a 45 clamp adapted to engage the side of a bath tub, a rod pivoted intermediate its ends to said clamp at a point such that when said clamp is secured to a tub said rod extends substantially its full length closely adjacent the side of the tub to 50 which said clamp is secured, said rod being pivotally movable about an axis substantially transverse to said rod in a substantially vertical plane extending longitudinally of the tub, a knob secured to said rod at one end thereof and serving as a handle for movement of said rod, the other 55 end of said rod being disposed transversely with respect to the remainder thereof, and a back washing device secured to said transversely extending portion of the rod, the radial distance 60 of the back engaging surface of said washing device from said pivot point being substantially the same as that of the knob from said pivot point.

5. A bath brush attachment comprising a 65 clamp adapted to engage the side of a bath tub, said clamp comprising a concave member adapted to engage the upper surface of the upper side edge of a tub of the type having a rolled upper edge and a clamping block curved to engage the under surface of said rolled upper edge, a rod pivoted to said clamp at a point such that when said clamp is secured to a tub said rod extends substantially its full length closely adjacent the side of the tub to which said clamp 70

is secured, said rod being pivotably movable about an axis substantially transverse to said rod in a substantially vertical plane extending longitudinally of the tub, said rod being provided with a handle portion and a portion disposed transversely with respect to the remainder thereof, and a brush secured to said transversely extending portion of the rod.

5. A bath brush attachment comprising a clamp adapted to engage the side of a bath tub, said clamp comprising two opposed clamping members adjustably secured to each other, and individual clamping means carried by one of said clamping means for completing the clamping operation after the relative position of said

10 clamping members has been adjusted to conform approximately with the thickness of the side of the bath tub, a rod pivoted to said clamp at a point such that when said clamp is secured to a tub said rod extends substantially its full length closely adjacent the side of the tub to which said clamp is secured, said rod being pivotably movable about an axis substantially transverse to said rod in a substantially vertical plane extending longitudinally of the tub, said rod being provided with a handle portion and a portion disposed transversely with respect to the remainder thereof, and a brush secured to said transversely extending portion of the rod.
